UNITED STATES PATENT OFFICE.

EARL M. TRAMMELL, OF EL PASO, TEXAS, ASSIGNOR TO EL PASO SASH & DOOR COMPANY, OF EL PASO, TEXAS.

DESIGN FOR A TELEPHONE CABINET.

Application filed June 27, 1927. Serial No. 22,584. Term of patent 14 years.

To all whom it may concern:

Be it known that I, EARL M. TRAMMELL, a citizen of the United States, residing in El Paso, in the county of El Paso and State of Texas, have invented a new, original, and ornamental Design for a Telephone Cabinet, of which the following is a specification, reference being had to the accompanying drawing, forming part thereof.

The figure is a perspective view of a telephone cabinet, showing my new design.

I claim the ornamental design for a telephone cabinet as shown.

EARL M. TRAMMELL.
